(57) **CLAIM**

The ornamental design for a bottle, as shown.

DESCRIPTION

FIG. 1 is a top, front and right side perspective view of a bottle showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The pattern shown on the bottom edge in FIGS. 2-5 & 7 is texture.
